COMFORT CHAIR

Filed Aug. 19, 1929

UNITED STATES PATENT OFFICE

JOHN A. SCHAUSS, OF NORWALK, OHIO, ASSIGNOR TO THE COMMERCE GUARDIAN TRUST
& SAVINGS BANK, AS TRUSTEE, OF TOLEDO, OHIO, A CORPORATION OF OHIO

COMFORT CHAIR

Application filed August 19, 1929. Serial No. 386,909.

This invention relates to adjustable position articles of furniture.

This invention has utility when incorporated in a comfort chair.

5 Referring to the drawings:

Fig. 1 is a side elevation of an embodiment of the invention;

Fig. 2 is a medial vertical section of the frame for the chair of Fig. 1;

10 Fig. 3 is a section on the line III—III, Fig. 2, looking in the direction of the arrow; and

15 Fig. 4 is a fragmentary detail view showing the stirrup and trigger as released for free positioning of the seat and back unit relatively to the base and arm unit of the chair.

Legs 1, 2, carry fixed therewith rectangular frame 3 as a base from which rises a pair of 20 arms 4 rigid with this base 3. The base 3 is shown as having forward side connecting brace 5 fixed with the base frame. Rearwardly from this brace 5, side portions of the frame 3 have fixed therewith blocks 6 25 carrying a straight line series of upwardly open notches 7 transversely in aligned pairs.

Seat 8 is mounted between the arms 4 and has rigid therewith back 9. This second unit 8, 9, is herein shown as disposed between the 30 arms 4 and provided with trunnions 10 laterally protruding therefrom in similar arc series coacting as to the central trunnions with the central notches 7 when the support is in upright position. As relative rocking 35 between the first and second unit occurs, these trunnions enter into or recede from the respective notches 7 in providing a rocking bearing between the pair of units.

The sides of the seat 8 have pivot pins 11 40 for links 12 having fastening means 13 assembling transverse block 14. These straps or links 12 and block 14 comprise a stirrup normally tending to swing downward. In set up position of the seat 8 and back 9, this stirrup 14 abuts ledge 15 of the base and provides a rigid lock in holding the structure as a fixed chair structure.

Externally the chair to all appearances is 45 that of a common rigid chair having upholstered seat 16, overstuffed seat cushion 17 and

upholstered arms 18 and upholstered back 19. However, to convert this apparently fixed chair into a comfort chair it is only necessary to pull the back 9 slightly forward as a rocking action for the back and seat unit relatively to the base and arm unit. This pull forward pulls the stirrup portion 14 clear of the ledge 15 and causes notch 20 in the stirrup 12, 14, to ride past nose 21 of trigger bar 22 having terminal trunnions 23 directly pivoted in the base 3. This rocking action for the chair brings the trigger nose 21 into notch 26 of the stirrup, so that in a rearward rocking of the back 9, the stirrup portion 14 rocks the bar 22 and the portion 14 is swung rearwardly clear of the ledge 15 to ride on surface 24. This will permit free rocking of the unit 8, 9, relatively to the unit 3, 4. The trigger bar 22 is counterweighted and as soon as free of the bar 14, the bar 22 rights itself by engaging stop 27 by its recess 28.

In practice, as a comfort chair, the tilting may be just to a desired angle for rest. At such position or even at an oscillating position, there is stability for quiet and substantial operation, in that the blocks 6 and trunnion 7 may be of wood, as well as the stirrup portion 14, and the trigger, thus leaving only the strips 12 as the assembly means thereof of a metal.

To bring the chair to a maintained or rigid set up position, the chair back 9 may be swung forward to permit the bar 14 to ride toward the trigger 22 and upon the ledge 15, the trigger bar forming an abutment against which the stirrup falls to determine the ledge abutting relationship. From this position, the rearward rocking of the back 9 causes the stirrup portion 14 to lodge against ledge 15. The position of rest for the trigger 20, 21, is determined by the stop 27 coacting with the recess 28 therein.

What is claimed and it is desired to secure by Letters Patent is:

1. In a chair, a base, a seat rockable thereon, a member carried by the seat swingable upon seat movement, a ledge carried by the base abutted by said member at one seat position to maintain said seat against rocking.

rearwardly, said member swingable from the ledge upon forward seat movement, and mechanism carried by the chair and operable on moving the seat forwardly a predetermined distance to swing the member clear of the ledge upon rearward movement of the seat.

2. A chair comprising a base unit, a seat unit rockable thereon, a stirrup mounted on the seat unit and swingable therefrom, a ledge carried by the base unit, said stirrup swingable to abut the ledge to resist one way rocking movement of the seat unit with movement the other way unresisted, said stirrup movable away from ledge abutting position upon movement of the seat unit in the unresisted direction, and a trigger carried by one of the units to engage the stirrup when moved from the ledge a predetermined distance and to carry said stirrup clear of the ledge in movement of the seat unit in the opposite direction.

3. A chair comprising a base unit, a seat unit, a rocker providing bearing therebetween, mechanism interacting between said units permitting free forward movement of said seat unit while restricting rearward rocking movement thereof, and control means operable by movement of one of the units to coact with said mechanism to permit free rocking movement in both directions.

4. A chair comprising a base unit, a seat unit rockable thereon, said units having a maintained position and a free rocking position, and mechanism interacting between said units comprising a swingable member on the seat unit, a ledge to be abutted thereby on the base unit in the maintained position, and means coacting with the swingable member during movement of the seat unit to carry the swingable member beyond the ledge for the free rocking position, said swingable member operable by seat unit movement for determining the position.

5. A chair comprising a base unit and a seat unit rockable thereon, an abutment carried by one of said units, and control means including a swingable member carried by the other of said units coacting against said abutment for maintaining said units against free movement therebetween and operable by a forward movement of the seat unit from a maintained position to move said member clear of the abutment, means engaging the member as moved clear of the abutment to cause said member to clear the abutment on the backward movement of the seat unit for permitting free rocking movement of said seat unit on the base unit.

6. A chair comprising a base unit and a seat unit rockable thereon, control means maintaining said units against free movement therebetween and operable by a normal forward movement of the seat unit from maintained position to release said means to per-

mit free rocking movement of said seat unit on the base, and reset means operable for returning the control means to holding position upon a second movement beyond normal forward rocking movement.

In witness whereof I affix my signature.
JOHN A. SCHAUSS.
